LADDER AND LOAD SUPPORTING DEVICE

Herbert M. Coddington, Morristown, N. J.

Application September 27, 1939, Serial No. 296,866

6 Claims. (Cl. 304—19)

My invention relates to ladder and load supporting devices adapted for use in connection with painting or repairing buildings and the like and has as one of the principal objects thereof the provision of a device of the above described character which is adapted for use in connection with ordinary ladders of any size without modifying the same and which is so constructed and arranged as to maintain or support the ladder a desired distance away from the building and at the same time support a load therebetween, for instance a scaffolding, platform or the like.

Another object of my invention is to provide a device of the above described character which is simple in construction, durable in use, efficient in operation and economical in manufacture.

Other objects and advantages will be apparent from the following description, appended claims and annexed drawings.

20 Referring to the drawings wherein like reference characters designate like parts throughout the several views:

Figure 1 is a side elevation of my invention illustrating the same as supporting a ladder adjacent to the side of a building and supporting a work platform therebetween.

Figure 2 is a sectional view taken on the line 2—2 of Figure 1.

Figure 3 is a rear elevation of my invention illustrating the latter attached to the upper section of a ladder.

Figure 4 is a side elevation of the inner end of one of the rods.

Figure 5 is a bottom plan view of one of the rods on an enlarged scale.

Figure 6 is a front elevation of one of the braces.

Figure 7 is a bottom plan view of said brace. In practicing my invention, as illustrated in the drawings, I provide a device 5 for supporting a ladder and load, for instance a platform 7, adjacent the side of a building 8 whereby said platform may be utilized by workmen for painting or otherwise repairing said building. The device 5 comprises a pair of spaced diverging rods 9 having outer angled ends 10, the latter being pointed whereby to enable the rods to firmly engage the side of the building.

The rods are also provided with inner angled ends 11 integrally fashioned and braced with cuffs 12 of a substantially rectangular configuration in plan and defined by side and end walls 13 and 14 respectively. The inner angled ends 10 of the rods 9 are fashioned with subjacent loops or eyed sections 15 adjacent the cuffs 12. Connected within said loops 15 are the hooked ends

16 of braces 17, the opposite ends of the latter being formed with angularly disposed eyed sections 18 arranged adjacent and in aligned relation with each other.

Both of the outer side and end walls of the cuffs 12 have extending therethrough clamping screws or bolts 19 for engaging the upper ends of the side rails 20 of the ladder 6 and which upper ends extend through the cuffs and are clamped in adjusted position therein by means of said 10 bolts 19.

The eyed sections 18 of the braces 17 are connected together and centrally between the side rails 20 of the ladder by means of a hook 21 swiveled to the upper pulley block 22 of a block 15 and tackle assembly 23, the lower pulley block 24 being connected to bracket arms 25 extending subjacent the platform 7 for supporting the ladder.

Obviously, the supporting device 5 serves to 20 support the ladder adjacent the sides of a building and at the same time supports the platform 7. When a pair or more of said devices are utilized in connection with a like number of ladders the platform is supported in horizontality with 25 respect to the building. In instances where it is only desired to raise and lower various objects, it is necessary to utilize only one ladder and one device. When one or more devices are thus utilized the weight of the load on the respective assemblies 23 is centralized between the rails of the ladder through the medium of the pulley block hook 21 being connected to the braces centrally between the rails of the ladder, thereby precluding lateral distribution of the weight with respect 30 to the ladder and resultant overturning or displacement of the ladder.

It is obvious that the invention is not confined to the herein described use therefor as it may be utilized for any purpose to which it is adaptable. 40 It is therefore to be distinctly understood that the invention is not limited to the specific construction as illustrated and described, as the same is only illustrative of the principles of operation, which are capable of extended application in advance forms, and that the invention comprehends all construction within the scope of the appended claims.

What I claim is:

1. In combination with a ladder having side 50 rails and adapted to be supported adjacent a building, a supporting device comprising a pair of diverging bars having outer angled ends for engagement with the building and inner angled ends formed with cuffs adjustably receiving said 55

5 side rails, and braces having ends detachably connected to said inner angled ends adjacent said cuffs and opposite ends disposed adjacent each other and adapted for connection with the supporting member of a pulley block to connect said opposite ends of said braces together centrally between said rails.

10 2. A ladder and load supporting device comprising a pair of diverging bars having outer angled ends for engagement with a building and inner angled ends formed with cuffs for receiving therethrough side rails of a ladder, and braces having ends detachably connected to said inner angled ends adjacent said cuffs and opposite ends disposed adjacent each other and adapted for connection with the supporting member of a pulley block to connect said opposite ends of said braces together centrally between said rails.

15 3. A ladder and load supporting device comprising a pair of diverging bars having outer angled ends for engagement with a building and inner angled ends formed with cuffs for adjust-

5 ably receiving the side rails of the ladder, said inner angled ends fashioned with loops adjacent said cuffs, and braces having hooked ends connected to said loops and opposite ends disposed adjacent each other and formed with eyes for receiving the supporting member of a pulley block to connect said opposite ends of said braces together centrally between said rails.

10 4. The elements of claim 1 as set forth and defined therein including, means carried by said cuffs for clamping said rails in adjusted positions within said cuffs.

15 5. The elements of claim 2 as set forth and defined therein including, means carried by said cuffs for clamping said rails in adjusted positions within said cuffs.

20 6. The elements of claim 3 as set forth and defined therein including, means carried by said cuffs for clamping said rails in adjusted positions within said cuffs.

HERBERT M. CODDINGTON.
